UNITED STATES PATENT OFFICE.

WILFRED C. PARRY, OF MARBLE, COLORADO.

METAL RAILROAD-TIE.

1,118,795.

Specification of Letters Patent Patented Nov. 24, 1914.

Application filed April 22, 1914. Serial No. 833,681.

To all whom it may concern:

Be it known that I, WILFRED C. PARRY, a citizen of the United States, and a resident of Marble, in the county of Gunnison and State of Colorado, have invented a new and Improved Metal Railroad-Tie, of which the following is a full, clear, and exact description.

This invention relates to railway equipment and has particular reference to cross-ties for railway rails.

Among the objects of the invention is to construct a railway tie principally of metal and provided with easily operated and reliable rail clamping devices.

The foregoing and other objects of the invention will hereinafter be more fully described and claimed and illustrated in the drawings forming a part of this specification in which like characters of reference indicate corresponding parts in all the views, and in which—

Figure 1 is a transverse section of a railroad track indicating one of my improved 25 cross-ties in side view; Fig. 2 is a longitudinal section of the crosstie on the line 2—2 of Fig. 3; Fig. 3 is a plan view of the same; Fig. 4 is an end view; Fig. 5 is a transverse sectional view of the crosstie on the line 30 5—5 of Fig. 3; Fig. 6 is a perspective view of one of the rail plates; Fig. 7 is a partial horizontal section on the line 7—7 of Fig. 5; and Fig. 8 is a detail of one of the rail braces or clamps.

The several parts of the device may be made of any suitable materials, and the relative sizes and proportions, as well as the general design of the mechanism, may be varied to a considerable extent without departing 40 from the spirit of the invention herein-after more fully described and specifically claimed.

Referring more particularly to the drawings, I show a preferred embodiment of my tie at 10, the same being shown as substantially tubular in form and rectangular in cross section. The ends of the tie are open, and except as herein later set forth the interior of the tie is hollow. Adjacent each 50 end of the upper portion of the tie is provided a seat 11 for a rail R. Said seat is

formed preferably by removing a portion of the upper or top plate of the tie, the outer edge of the seat being undercut, forming a lip 12 adapted to overlap the base flange of 65 the rail, and thereby preventing the tilting of the rail inwardly toward the opposite rail. The inner side of the seat 11 or the edge opposite the lip 12 is far enough remote to allow ample room for introducing the 60 rail and clamping devices.

The rail brace 13, shown in detail in Fig. 8, comprises preferably a hollow box-like structure having on its bottom outwardly projecting flanges 14 which are adapted to 65 project beneath a pair of shoulders 15 extending parallel to each other and to the longitudinal axis of the tie outwardly from the lip 12. As shown in Fig. 8, the flanges 14 may be formed by bending the vertical sides 70 16 of the brace 13 inwardly toward each other on the horizontal plane and thence downwardly and outwardly, providing parallel horizontal grooves 15' for coöperation with said shoulders 15. The coöperation between the brace and the portion of the top plate of the tie adjacent the lip 12 constitutes a positive lock preventing the brace from upward or outward movement from its normal position, the outer end 17 of the 80 brace being adapted to abut against the main portion of the plate at the end of the shoulders 15. The lower inner portion of the brace is preferably beveled so as to fit snugly upon the rail base flange as indicated at 18. 85

At 19, in Fig. 6, I show a detail view of one of a pair of similar rail plates. Each plate comprises a main portion 20 adapted to receive the rail directly thereupon adjacent the seat 11 aforesaid and a shank 21 90 formed preferably integrally therewith extends inwardly therefrom approximately to the center of the track or mid portion of the tie. The inner end of the shank is provided with a horizontal slot 22 forming a shoulder 23. The outer end of the rail plate is rounded or beveled at its lower end as shown at 24, and directly above the bevel at the longitudinal center of the plate is a seat 25 to accommodate the interlocking flanges 14 of 100 the rail brace.

At 26 I show an inner rail clamp formed

in any suitable manner upon the plate 20 and preferably in a rigid manner. Said clamp 26 is adapted to conform to and co-operate directly with the inner edge of the base flange of the rail R when the rail plate is forced upwardly along the tie. The rail clamp 26, together with the plate 20, constitutes a positive locking means for the rail and through the rail for the brace 13.

10 As shown in Figs. 5 and 7 particularly, the slotted portions or inner ends of the shanks 21 overlap each other at the center of the tie, and the slots 22 of the overlapping shanks coming into alignment with each other provide a seat for a peculiar form of locking wedges 27 and 28. These wedges are arranged in pairs and extend horizontally through slots 29 formed in the side walls of the tie. Each wedge comprises a structure having one edge 30 substantially perpendicular to the axes of the shanks and is adapted to abut against a shoulder 23 of one shank and the end 31 of one of the slots 29 while the opposite edge 32 of the wedge 28 is oblique to the edge 30. The other wedge co-operates similarly with the other shank shoulder and corresponding point 31 on the opposite side of the crosstie. I prefer also to provide a lug 33 at the large end of each 30 wedge at the end of the straight side 30 thereof to prevent the wedge from being forced too far through the tie. At 34 I provide a series of notches along the oblique side 32 of each wedge, the notches of one 35 wedge being adapted to register with those of the other when the wedges are driven home, and a pin 35 is adapted to be passed through a pair of said notches to lock the wedges in position. Said pin may be in the 40 form of a bolt having a nut 36 or other fastening means to hold it in place. The action of the wedges related, as above described, to the shanks of the rail plates causes the plates to be forced apart, each 45 being forced snugly under its rail and with its clamp 26 gripping the base flange as stated, making a rigid connection for both sets of clamps and braces.

50 At 37 I show a cushion in the form preferably of a wooden block which is adapted to be forced through the open end of the tie and beneath the main portion of the rail plate 20. The bevel 24 serves to facilitate the introduction of the block without mutilating the block or changing its rectangular form, and hence insuring the full supporting strength for the block. By driving the block snugly into position, it serves as a slightly 55 resilient cushion for the rail supported thereupon through the plate 20. The block may be held in place by any suitable means such, for instance, as by a spike 38 driven through a hole 39 in the top of the tie. A notch 60 at the end of the tie provides means for

introducing a crowbar or other implement 65 for the purpose of withdrawing the block when desired.

Having thus described my invention, I claim as new and desire to secure by Letters Patent:—

70 1. The herein described railway tie comprising a tubular metallic body having seats formed in its upper portion, a pair of rail plates co-operating within the tie and adjacent said seats, each plate having a rail clamp secured thereto for co-operation with one edge of the base flange of the rail, means acting between the rail plates to force them apart outwardly in locking position, a rail brace interlocking with the portion of the 80 tie above the rail plate and on the outside of the rail, and cushion means within the tie serving to support the rail plates and rails.

85 2. The combination with a pair of rails, of a combined crosstie and rail clamp, the same comprising a hollow rectangular body having seats formed in its upper portion for the rails, rail plates co-operating with the upper portion of the tie and adapted to directly support the rails, a detachable rail brace co-operating with the outer side of each rail and interlocking with the tie above the adjacent plate, means co-operating with the rail plates serving to force them apart into 90 gripping relation to the rails, and a wooden block forced into each end of the tie snugly beneath the adjacent rail plate, substantially as set forth.

95 3. In a metal crosstie construction, the combination of a hollow body having a flat upper surface, said surface being cut away forming a seat for a rail, a rail plate slideable along the inner surface of the upper part of the body, said plate having a rail 100 clamp fixed thereto for co-operation with the inner edge of the rail base flange, the outside portion of the seat being notched between the side edges of the rail, a rail brace having outwardly projecting flanges adapted to interlock with the edge portions of said notch in close proximity to the outer end of the plate, and means to force the plate into normal gripping position, substantially as set forth.

115 4. In a crosstie construction for railway rails, the combination of a metallic body having a pair of aligned slots 29 formed in its sides intermediate its ends, the upper portion of the body being cut away forming 120 rail seats, a pair of rail braces interlocking with the top of the crosstie at the outer edges of said seats and co-operating with the outer edges of the base flanges of the rails, a pair of rail plates slideable longitudinally of the body beneath the rails, each plate having a fixed clamp co-operating with the inner edge of the rail, said plates having 125

inwardly projecting and overlapping slotted shanks, a pair of wedges passing through said first mentioned slots and the shank slots coöperating therewith to force the plates 5 outwardly away from each other into gripping position, and means to lock the wedges in position, substantially as set forth.

In testimony whereof I have signed my name to this specification in the presence of two subscribing witnesses.

WILFRED C. PARRY.
